LESLIE E. PETERS, OF SAN FRANCISCO, CALIFORNIA

FUEL CONTROL MEANS FOR HEATING APPARATUS

Application filed January 27, 1930. Serial No. 423,750.

This invention relates to improvements in thermostatic control means for heaters.

An object of my invention is to provide improved thermostatic control means for regulating the flow of fuel to burners.

Another object of my invention is to provide improved thermostatic control means for regulating the flow of fuel to a pilot burner.

10 A still further object of my invention is to provide improved thermostatic control means for use with heating apparatus wherein novel means is employed for shutting off the flow of fuel to a burner when a pilot light 15 has been extinguished.

Other objects more or less apparent will present themselves or will be specifically pointed out in the description to follow.

In the accompanying drawing the figure is 20 a vertical cross sectional view of a thermostatic control means constructed in accordance with my invention.

Referring to the drawing the numeral 1 represents an air tight rectangular shaped 25 casing through which quantities of gaseous fuel may pass. Screwed into the top side of the casing at one end thereof is a pipe 2 which is connected at a point outside the casing with a water carrying pipe 3, the said 30 water carrying pipe being ordinarily connected to a water heater. Located inside the water carrying pipe 3 is a thermostatic control means comprising the usual copper tube 4 having a metal or glass rod 5 therein. The 35 rod 5 is actuated downwardly upon the contraction of the copper tube and upwardly upon the expansion of the said tube, the latter being expanded by warm or hot water passing through pipe 2, or contracted by cold 40 water in the said pipe.

Slidably extending through the bottom of the casing 1 and through a suitable packing gland thereon, in line with the rod 5, is a vertical shaft 6 having a threaded opening in its upper end for the attachment of the downwardly disposed end of the rod 5. The upper end of the shaft is provided with two spaced circular projections 7 between which an end 50 of a lever member 8 is positioned, the said

lever member being mounted on a pivot 9 carried by the casing.

The bottom of the casing 1, at an end opposite to that end where the shaft 6 is located, is provided with a threated recessed projection 10 within which a cup shaped partition member 11 is screwably and adjustably positioned. The top edge of the partition member is provided with a circular seat 12 which normally projects above the bottom of the casing. The partition member is provided with a downwardly disposed extension 13 which extends through a suitable packing gland 14. The partition member may be adjustably moved upward or downward by 60 turning the extension 13 in the proper direction with a wrench or other tool. The recessed projection 10 is provided with a fuel inlet 15, the said fuel being adapted to pass to the inside of the casing through a number 65 of openings 16 located in the partition member 11. The upper ends of the openings 16 are positioned beneath the seat 12 on the partition member, this being to prevent fuel from passing through the openings when a disc 70 is seated on the seat.

The top side of the casing 1, at a point directly above the recessed projection 10 on the bottom, is provided with a recessed projection 17 having a fuel outlet 18. The chamber located in the recessed projection 17 communicates directly with the inside of the casing, thereby providing a continuous passageway for the movement of fuel from the casing to the outlet 18. The inside or lower surface of the top of the casing at a point beneath the recessed projection 17 is provided with a circular flange 19 which forms a seat on which a disc may rest to prevent fuel from passing from the casing into its recessed projection 75 17.

The lever member 8 is provided at an end thereof with a steel spring 20 which is secured to an upright bar 21, the ends of which are pivotally attached to discs 22 and 23. The disc 22 is adapted to rest on seat 12 to prevent fuel from passing into the casing while the disc 23 is adapted to contact with the seat on flange 19 to prevent fuel from passing 80 from the inside of the casing.

Secured to the top of the recessed projection 17 is a T-shaped flange 24 having a horizontal opening 25 therethrough as well as a vertical opening entirely therethrough. Suitably secured to the flange 24 at points where the ends of the opening 25 occur, are pipes 26 and 27, the former pipe leading from a suitable source of gaseous fuel and the latter pipe leading to a pilot burner mounted in the heating apparatus. Moveably mounted in the vertical opening in the T-shaped flange 24 is a rod 28, the lower part of which projects through the chamber in the recessed flange 17 and has its downwardly disposed end contacting with the disc 23. The upper end of the rod 28 projects above the end of the vertical opening in the flange 24 and is normally in contact with an end of a pivoted top-heavy lever 29. The rod 28 is provided with a cut out part or groove 30 which is normally adapted to register with the opening 25 in the T-shaped flange to allow fuel to pass through the pipes 26 and 27 to the pilot burner. At certain times, as will be later described, the rod 28 moves upwardly to carry the groove 30 out of registry with the opening 25, thereby preventing the passage of fuel through the said opening to the pilot burner.

When it is desired to commence the operation of the heating apparatus to which the control valve is attached, the lever member 29 is moved upwardly to a position shown by the dotted lines, thereby causing the rod 28 to move downwardly to the position indicated by the dotted lines. As the said rod moves downwardly the groove 30 therein is carried into registry with the opening 25 in the T-shaped flange 24, thereby allowing gaseous fuel to proceed through the pipes 26 and 27 to the pilot burner. The rod 28 in moving downwardly, forces the discs 23 and 22 against the tension of spring 20 in a downward direction, thereby causing the disc 23 to become unseated or removed from the seat on the flange 19. The unseating of the disc 23 permits quantities of gaseous fuel to proceed from the inlet 15 through the chamber in the recessed projection 10 to the inside of the casing, from whence it then passes through the chamber in the recessed projection 17 to the outlet 18. The fuel passing through the outlet 18 proceeds to the heating apparatus and is thereupon ignited by the flame at the pilot burner. As the water in the heating apparatus becomes heated it passes through the pipes 3 and 2 and around the copper tube 4, thereby causing the said tube to expand and the rod 5 to move in an upward direction. The movement of the rod 5 in an upward direction also causes the shaft 6 with its flanges 7 to move upwardly, thereby moving the lever member 8 about its pivot 9 in such a manner that the spring 20, the bar 21 and the discs 22 and 23 are moved in downward directions. The particular position of

the partition member 11 with reference to the disc 22 will control the amount of movement necessary to cause the said disc to contact with the seat 12 on the said partition member. Thus if the partition member 11 is screwed upwardly the disc 22 will not have to travel in a downward direction for such a great distance in order to contact with the seat 12. The partition member 12 being capable of adjustment, provides suitable means for shutting off the flow of fuel to the heating apparatus upon the water therein reaching a certain maximum temperature. Therefore as soon as the water passing through pipes 3 and 2 has reached a certain maximum temperature the rod 5 will have been moved upwardly sufficiently to cause the disc 22 to contact with the seat 12 and discontinue the flow of gaseous fuel from the casing to the outlet 15. Upon the shutting off of the gas flow to the heating apparatus the water passing through pipes 3 and 2 becomes cooled, thereby causing the contraction of copper tube 4 and the downward movement of the rod 5. If the rod 5 moves to an extreme upward position, as shown by the full lines, the disc 23 is carried to a position where it engages with the seat on flange 19, thereby preventing the flow of fuel from the casing. The amount of travel necessary to cause the disc 23 to engage with flange 19 may be regulated by screwing the shaft 6 farther on or off the rod 5. This adjustment serves to govern the minimum temperature at which water must be to prevent the flow of gas to the inside of the casing. In ordinary practice and normally the adjustments of the partition 11 and the shaft 6 will enable the discs 22 and 23 to be positioned between their two seats without contact being made therewith, thereby allowing the fuel to pass from the inlet 18 through the casing and the outlet 18 to the heating apparatus. Owing to the fact that the pilot burner normally maintains the water in the heating apparatus in a slightly preheated state, the rod 5 is not moved downward sufficiently to cause the disc 23 to engage with its seat on flange 19. Should the gas supply be shut off at the source, the thermostatic means operates to move the disc 23 upwardly against the seat on flange 19, thereby elevating the rod 28 and causing the closing of the opening 25 through the T-shaped member 24.

After the disc 23 had been moved downwardly by the lever member 29 and the water in the heating apparatus reaches a sufficient temperature to move the rod 5 upwardly to remove the tension on spring 20, the pressure of the disc 23 against the rod 28 is relieved, thereby permitting the lever member 29 to drop by its own weight to a horizontal position as indicated by the full lines.

Having described my invention what I claim is:

1. Fuel control means comprising a cas-

ing having a fuel inlet and a fuel outlet, a projecting member mounted on the casing having an opening extending therethrough, a plurality of connected discs mounted in the 5 casing for opening and closing the inlet and outlet openings, thermostatic control means mounted on the casing for actuating the discs, a rod moveably extending through the projecting member having means for opening

10 and closing the opening through the projecting member, one end of the rod being in contact with one of the discs and the other end being positioned above the projecting member, and a lever member mounted on the 15 projecting member for moving the rod to position a disc away from the outlet opening and to open the opening through the projecting member.

2. Fuel control means comprising a casing 20 having a fuel inlet and a fuel outlet, a plurality of connected discs moveably mounted in the casing for closing and opening the inlet and outlet openings, thermostatic control means mounted on the casing for actuating the discs, means for delivering fuel 25 to a pilot burner, a rod for actuating the discs, the said rod carrying means for controlling the passage of fuel through the means for delivering fuel to the burner, and 30 a lever for moving the rod.

3. Fuel control means comprising a casing having fuel inlet and outlet means therein, a disc for regulating the flow of fuel through the casing, thermostatic means for 35 moving the disc, fuel supply means leading to a pilot burner, a rod for moving the disc to a position whereby fuel is prevented from proceeding through the casing, means carried by the rod for controlling the movement 40 of fuel through the fuel supply means, and a lever member for actuating the rod.

4. In fuel control means, a casing having fuel inlet and outlet means, thermostatic controlled means mounted in the casing for automatically regulating the flow of fuel through the casing, manually operated means for moving the thermostatic controlled means to a position whereby fuel is prevented from passing through the outlet means, fuel supply 50 means leading to a pilot burner, and means carried by the manually operated means for preventing fuel to proceed through the said fuel supply means when the said manually operated means has been manually moved to 55 a certain position.

5. Fuel control means comprising a casing having inlet and outlet means therein, thermostatic controlled means mounted in the casing for automatically regulating the 60 flow of fuel through the casing, manually operated means for moving the thermostatic controlled means to a position whereby fuel is prevented from passing through the outlet means, fuel supply means leading to a 65 pilot burner, means carried by the manually

operated means for preventing fuel to proceed through the said fuel supply means when the said manually operated means has been manually moved to a position whereby the outlet means is closed, and spring means for returning the manually operated means to a position whereby the fuel supply means may again conduct fuel to the pilot burner.

70 In testimony whereof I have affixed my signature.
